UNITED STATES PATENT OFFICE.

WILLIAM H. WOOD, OF MEDIA, PENNSYLVANIA.

BOILER.

1,166,908.

Specification of Letters Patent. Patented Aug. 11, 1914.

Application filed October 16, 1913. Serial No. 725,242.

To all whom it may concern:

Be it known that I, WILLIAM H. Wood, a citizen of the United States, and a resident of Media, county of Delaware, and State of Pennsylvania, have invented an Improvement in Boilers, of which the following is a specification.

My invention has reference to steam boilers and consists of certain improvements which are fully set forth in the following specification and shown in the accompanying drawings which form a part thereof.

The object of my invention is to provide a boiler construction having reference more particularly to locomotives which shall strengthen the fire box structure in such a manner that weakening of or distortion of the tube sheets adjacent the tube area is eliminated while at the same time the flexibility of the fire box structure is materially increased without impairing its resistance to strains and stresses caused by the enormous power exerted by the contraction and expansion of the boiler tubes relative to the boiler shell.

In boilers as heretofore constructed it has been found in practice that flat plates which are drawn to the extended lengths of the modern locomotive practice, weaken and crack under the constant expansion and contraction of the tubes and cause breaking of the stay-bolts that hold the plates together. In some instances flexible stay-bolts have been used to accommodate the movement of the flat plates, but owing to the fact that it is not possible to adjust all the stays in the breaking zone of the fire box to have equal tension on the plates, it has been found that substantially all the strain of the loose tension of the flexible stays has to be taken by the fixed stays, with the consequent result that the said fixed stays are not able to withstand the excess pressure. It has further been found in practice that while flexible plates have to a large extent overcome the aforesaid defects, they are open to the objection that the weight of the tubes together with the overheating is such as to cause the said plates to become distorted under the strains of expansion and contraction, and thus in a measure detract from the advantages gained by the use of the flexible plate construction.

In my present invention I have overcome the foregoing defects and dangers and provided a construction eliminating the use of

flexible stay-bolts and also materially decreasing the number of fixed stays, all of which is made possible without sacrificing flexibility of the tube sheet or impairing the free expansion and contraction of the tubes.

My invention comprises, more specifically, constructing the fire box sheets of corrugated material which combines an increased sectional area with great flexibility and incorporating in the fire box tube sheet a corrugation or groove portion which substantially encircles the tube area and merges into the throat sheet, the said groove portion being reinforced and strengthened at suitable points with brackets or like devices which added to the normal resistance of the sheet serve to prevent buckling or distortion of the throat sheet under the weight of the tubes when the said sheet is subjected to overheating.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized, and that my invention is not limited to the precise arrangement and organization of these instrumentalities as herein shown and described.

Figure 1 represents a longitudinal sectional elevation of a portion of a boiler embodying my invention; Fig. 2 represents an end elevation of the same, a portion thereof being shown in an enlarged transverse section; Fig. 3 represents a perspective of one of the reinforcing devices; Fig. 4 represents an elevation of a portion of the throat tube plate showing one form of reinforcing device in operative position; Fig. 5 represents a similar elevation showing a modified type of reinforcing device.

1 designates the outer shell of a boiler which, in the present instance, is of the locomotive type and incloses at one portion thereof the fire box shell 2 which latter with the back sheet 3 and front or tube sheet 4 form the fire box 5. 6 designates the usual fire tubes secured to the tube sheet 4 and extending longitudinally of the boiler, as will be readily understood. The sides and crown

sheet forming the outer barrel 2 of the fire box may be formed with a series of parallel corrugated or grooved portions 7 to give flexibility in the direction of the length of the boiler, while between or intermediate the adjacent corrugations there is a flattened portion 8 which provides a suitable space for the stays 9 by which the shell 2 is stayed to the sides and top of the boiler shell 1. 10 The corrugations 7 are preferably terminated a short distance above the bottom edge of the sheet in order to provide for the rivets 10 which secure the sheet to the mud ring 11. The body of the tube sheet 4, exterior to 15 the area occupied by the tubes, is reversely curved or flanged to form a groove or curved offset portion 12, which gives an increased heating surface and provides for expansion and contraction of the tubes so that the tube 20 sheet may be moved under such action without danger of rupturing the flanged joint. At the bottom of the tube sheet 4, and where the said tube sheet merges into the throat sheet 13, the curved offset portion is continued so as to increase the flexibility to take 25 care of the aforesaid expansion and contraction, and I have along this portion provided a plurality of reinforcing brackets 14 which are spaced apart a suitable distance 30 and extend throughout substantially the length of the throat sheet 13. These brackets 14 are curved in a manner corresponding to the flanged offset 12 and are adapted to seat upon the offset with a snug 35 fit, being either riveted or welded to the tube sheet 4 and throat sheet 13. In Fig. 4 I have shown the reinforcing brackets 14 riveted as shown at 15, while in Fig. 5 the said brackets are welded directly to the 40 sheets. The function of these brackets 14 is to strengthen the junction between the tube sheet and the throat sheet, since it will readily be understood that this portion of the sheet is not only exposed to the intense heat 45 of the fire box but is also subjected to the weight of the tubes 6 which are secured to the tube sheet 4. In effect the offset portion 12 is a curved corrugation which substantially encircles the tubes 6 and has the most 50 unusual and trying conditions to contend with since its normally overheated condition, together with the weight of the tubes renders it exceedingly liable to become distorted or buckled on its lower circumference. By 55 providing a plurality of the brackets 14 the corrugation or offset 12 is strengthened, at all the necessary points and the aforesaid danger of distortion in use is practically eliminated, while at the same time the increased heating surface of the backhead is 60 preserved, and there is a decided gain in flexibility. Furthermore, by this construction the number of stay-bolts required is reduced to a minimum without in any manner 65 impairing the factor of safety of the boiler

and rigidity effectively maintained at one place while flexibility is given at another. As a further means for increasing the strength of the throat sheet 13 I have preferred to provide a plurality of substantially vertical corrugations 16 which extend at suitable intervals from one side of the sheet to the other beneath the offset corrugation 12. 70

Referring now to the back sheet 3, it will be noted that I have provided the same with a plurality of corrugations 17 giving increased heating surface to this sheet and also providing flat portions between adjacent corrugations for the water leg stay-bolts 18. 75

It will now be apparent that I have provided a complete unitary structure particularly well adapted for the present-day extended fire boxes and which provides for a flexibility not heretofore attained, whereby the tubes have free expansion and contraction without affecting the supporting sheets or causing distortion thereof, and without developing weakness in the surrounding structure. Furthermore, these advantages are obtained without varying the customary 80 tube construction, since the changes embodied in my invention have all been made outside of the tube area and without enlarging the general cross section of the fire box. 85

While I have shown the construction of my invention in connection with a locomotive type of boiler, it is to be understood that my invention is intended for use with all types of tubular boilers, and while I prefer the construction herein disclosed and set forth, the details thereof may be modified 90 without departing from the spirit of the invention. 95

Having thus described my invention, what 100 I claim and desire to secure by Letters Patent of the United States is:—

1. In a steam boiler, a tube sheet having a series of apertures for the tubes and provided with a corrugation substantially encircling the apertured area, and means for reinforcing said tube sheet along said corrugation. 110

2. In a steam boiler, a tube sheet having a series of apertures for the tubes and provided with a corrugation substantially encircling said apertured area and also having a plurality of corrugations below said encircling corrugation, and means for reinforcing said tube sheet along said encircling corrugation. 115

3. In a steam boiler, a tube sheet having a series of apertures for the tubes and provided with a corrugation encircling the apertured area, and a plurality of reinforcing brackets secured to said tube sheet and disposed at suitable intervals along said corrugation. 125

4. In a steam boiler, a tube sheet having a series of apertures for the tubes and pro- 130

vided with a corrugation substantially encircling said apertured area, and a plurality of reinforcing brackets straddling said corrugation and secured to said tube sheet.

5. In a steam boiler, a fire box comprising a tube sheet and a throat sheet, and provided with a corrugation having a portion located at the junction of said tube sheet with said throat sheet and substantially encircling the tube area, said throat sheet having a plurality of substantially vertically arranged corrugations, and a plurality of brackets straddling said encircling corrugation and secured at one end to said tube sheet, and at the other end to said throat sheet.

6. In a boiler, a fire box having a back sheet wider at the bottom than at the top and provided with a flanged fire door aperture and a plurality of corrugations ar-

ranged in generally vertical direction above and below said door aperture and also at each side thereof and extending into close proximity to the top and bottom of said back sheet, said corrugations inclining toward each other at the upper part of the sheet, and all of said corrugations being spaced independently apart and providing between them flat portions of the sheet having a general upright direction, combined with stay-bolts secured into the flat portions of the sheets between the corrugations.

In testimony of which invention, I hereunto set my hand.

WM. H. WOOD.
